UNITED STATES PATENT OFFICE.

GEORGE W. CRAVENS, OF SCHENECTADY, NEW YORK, ASSIGNOR TO GENERAL ELECTRIC COMPANY, A CORPORATION OF NEW YORK.

LIQUID-RHEOSTAT.

No. 832,720.

Specification of Letters Patent.

Patented Oct. 9, 1906.

Application filed October 21, 1905. Serial No. 283,731.

To all whom it may concern:

Be it known that I, GEORGE W. CRAVENS, a citizen of the United States, residing at Schenectady, county of Schenectady, State of New York, have invented certain new and useful Improvements in Liquid-Rheostats, of which the following is a specification.

This invention relates to liquid-rheostats for controlling electric motors, and has for its object the provision of a device of this character which is adapted to a variety of uses in connection with both the starting and running of motors and which will be cheap of construction, simple of operation, and at the same time thoroughly efficient, safe, and durable.

My invention relates more specifically to water-rheostats for use in connection with alternating-current motors, and is well adapted for use in connection with polyphase induction-motors, although it is capable of general use. Water-rheostats are very useful, especially where heavy currents are to be regulated or where a heavy load from a generator is to be absorbed, as in a case where the machines are being tested. Liquid-rheostats as hereinbefore designed for alternating-current service have provided simply for the regulation of the resistance of the system as a whole and no provision is made for varying the load in each leg of the system independently of the others.

In carrying out my invention I provide a liquid-rheostat in which the resistance in the entire system is varied by a single operation, and in addition to this I provide means for varying a resistance in any one leg of the system without interfering with the resistance in the other leg. I also provide a rheostat in which the conducting elements are made tapering or cone-shaped, the advantages of which arrangement will be obvious to one skilled in the art.

My invention therefore consists in the features of construction and the arrangement and combination of elements hereinafter set forth, and particularly pointed out in the claims annexed to and forming a part of this application.

In the drawings, Figure 1 is a sectional view of a liquid-rheostat embodying my invention. Fig. 2 is a plan view of the same. Fig. 3 is a detail showing the construction of the tank-partitions. Fig. 4 shows the yoke for connecting the sections of the hood, and Fig. 5 shows the terminal connections.

Referring to the drawings, 10 is a receptacle or tank, preferably circular in shape, for containing the water and may be of any suitable material. I have shown this tank as made of wood, since in the particular type of rheostat illustrated it is essential that the tank itself be of insulating material. The tank is divided into three compartments by means of the partitions 11, 12, and 13. This arrangement of course may also be varied to suit the conditions and kind of current to be regulated. The device as shown is intended for three-phase current, and therefore three sets of conducting elements are required. Within each compartment is one of the tapering or conical metallic elements 14, 15, and 16, each provided with a flanged portion 17 for supporting the element upon the bottom of the receptacle. These elements are adapted to slide radially from the center of the tank, and for accomplishing this I provide a screw 18, threaded into a hub in the flange 17 and having a bearing in the tank at 19. A handle 20 is provided for each screw, so that by turning the handle each element may be adjusted in its compartment. Three correspondingly-shaped elements 21, 22, and 23 are provided, one for each compartment. These elements are shaped in the form of a hood and connected at the top by means of U-shaped straps 24. They are also provided with flanged portions 25, which rest upon the flanges of the sliding elements when the upper element is lowered into contact with the lower one. The flange of the hood is cut away at 26 so as to fit over the hub in the lower flange. The three elements are connected together by means of a triangular yoke 27, which is provided with a Y-shaped casting 28 for attachment with an adjusting-cable 29. By means of this cable the three elements may be moved up and down in the vessel together, so as to vary the resistance between each pair of elements in a compartment.

Each element 14, 15, and 16 forms an electric terminal, connection with which is made as shown in Fig. 5. The current passes from the conducting-wire 30 to the element through the bearing 31 and screw 18. The partitions forming the compartments extend nearly to the top of the tank and are cut away, as at 32, to allow the water to circulate from one compartment to the other.

The operation of my device will be clearly

understood from the foregoing description. By lowering and raising the yoke 27 by means of the cable 29 the conical elements are caused to approach and recede from each other, so as to vary the resistance between them when the tank is filled with water. When the movable elements are lowered into the tank and it is desired to vary the load in any leg of the system, this may be done by means of the handle 20.

In the arrangement shown the elements 21, 22, and 23 are electrically connected together, so as to form them into a common neutral. I do not, however, limit my invention to this particular construction, since it is clear to one skilled in the art that these elements need not be electrically connected, as it is not essential that a common neutral be formed. It should be further understood that I do not limit my invention to an insulating-tank nor to the particular arrangement of elements or mode of operation except as it is limited by the claims annexed hereto.

What I claim as new, and desire to secure by Letters Patent of the United States, is—

1. A liquid-rheostat comprising a plurality of conducting elements, a common neutral element, and means for varying the resistance between one of said conducting elements and the common neutral independently of the others.

2. A liquid-rheostat comprising a plurality of conducting elements, a common neutral element, means for varying the resistance between the common neutral and all of the conducting elements simultaneously, and means for varying the resistance between the common neutral and one of said elements independently.

3. A liquid-rheostat comprising a receptacle for the liquid, a plurality of pairs of tapering conducting elements therein, and means for independently adjusting the elements of each pair.

4. A liquid-rheostat comprising a plurality of tapering conducting elements, a similarly-shaped common neutral conductor, and means for varying the distance between the conducting elements and said common neutral.

5. A liquid-rheostat comprising a plurality of tapering conducting elements, a similarly-shaped common neutral conductor, and means for varying the distance between one of the conductors and the common neutral independently of the others.

6. A liquid-rheostat comprising a plurality of tapering conducting elements, a similarly-shaped common neutral element, means for varying the distance between the tapering elements and the common neutral simultaneously, and means for varying the distance between one of said elements and the common neutral independently of the others.

7. In a water-rheostat, the combination

with a receptacle for the water, of a plurality of conducting elements therein adjustable with respect to each other, and a conducting element common to said adjustable elements and movable to and from the same.

8. In a water-rheostat, the combination with a receptacle for the water, of a plurality of conducting elements therein, a common neutral conductor, and means for varying the resistance between any one of said conducting elements and the common neutral.

9. In a water-rheostat, the combination with a receptacle for the water, of a plurality of pairs of conducting elements therein, and means for varying the arrangement of the elements of a pair independently of the others.

10. In a water-rheostat, the combination with a plurality of compartments for the liquid, of a pair of conducting elements in each compartment, and means for varying the arrangement of the elements of a pair independently of the others.

11. In a water-rheostat, the combination with a plurality of compartments for the liquid, of a pair of tapering conducting elements in each compartment, and means for varying the arrangement of the elements of a pair independently of the others.

12. In a liquid-rheostat, the combination with a receptacle for the liquid, of a plurality of pairs of conducting elements therein, means for varying the arrangement of the elements of all of the pairs simultaneously, and means for varying the arrangement of the elements of each pair independently of the others.

13. In a water-rheostat, the combination with a receptacle for the water, of a plurality of tapering conducting elements therein, a similarly-shaped common neutral element, and means for varying the distance between said common neutral and any one of the conducting elements independently of the others.

14. In a water-rheostat, the combination with a receptacle for the water provided with compartments, of a conducting element in each compartment, a common neutral element movable in said compartments to and from said conducting elements, and means for varying the distance between said neutral element and any one of said conducting elements independently of the others.

15. A liquid-rheostat comprising a receptacle for the liquid, a plurality of tapering elements therein movable in a horizontal plane, and a correspondingly-shaped member common to said elements and movable toward and from the same in a vertical plane.

In witness whereof I have hereunto set my hand this 18th day of October, 1905.

GEORGE W. CRAVENS.
